UNITED STATES PATENT OFFICE.

HOWARD M. VAN ALSTYNE, OF RENSSELAER, NEW YORK.

SLIDING-DOOR FASTENER.

Application filed August 2, 1922. Serial No. 579,296.

To all whom it may concern:

Be it known that I, HOWARD M. VAN ALSTYNE, a citizen of the United States, and a resident of Rensselaer, in the county of Rensselaer and State of New York, have invented a new and Improved Sliding-Door Fastener, of which the following is a full, clear, and exact description.

This invention relates to a car door post construction, and has for an object the provision of a construction to reinforce a door, such as the sliding side doors of freight cars.

Another object of the invention is to provide a door construction so designed as to require a minimum number of parts, all easy of access, and combining ease and simplicity of operation with ruggedness and strength of construction.

A further object resides in the provision of means whereby the door when moved to closed position can be very easily locked in every direction and will also be efficiently reinforced.

A still further object resides in the particular construction and arrangement of parts which are hereinafter described and claimed and shown in the accompanying drawings.

The invention is illustrated in the drawings, of which—

Fig. 1 is a side elevation of the doors of a freight car showing the door which carries the post in its closed position.

Fig. 2 is a section taken on the line 2—2 of Fig. 3.

Fig. 3 is a longitudinal vertical section taken through the lower end of the post construction.

Fig. 4 is a section taken on the line 4—4 of Fig. 3.

The form of the invention shown in the drawings is a preferred form, although it is understood that modifications in the construction and arrangement of the parts and in the character of the materials used may be adopted without departing from the spirit of the invention.

A preferred form of the invention, as shown in the drawings, is applied to a sliding freight car door, and it involves the use of a steel channel member 1, preferably U-shape as shown in Fig. 4, one of the legs of which is bolted to the inside of the end of the car door 2. This channel beam or member 1 extends along the inner face of the door 2 from the floor of the car to the top of the door and acts as a reinforcement or stiffen-

ing means for the door. Over the lower and upper ends of this channel plate or stiffening member 1 I pass a U-shaped strap 3 provided with an aperture 4. The legs of this strap 3 may be suitably fastened, as by rivets 5, to the lower end of the reinforcing member 1.

Associated with both the upper and lower ends of the stiffening member 1 are a pair of locking plungers such as 6. These plungers are actuated by links 7 connected to an operating arm pivoted at 8 to the stiffening member 1 or to the door 2. These plungers or bolts 6 are so disposed that when the arm 8 is in the approximately horizontal position shown in Fig. 1, the bolt 6 will be withdrawn from suitable openings formed between channel plates 10 and 11 which are disposed within the lower and upper ends of the stiffening member 1. Each of these channel plates 10 and 11 are formed of U-shaped plates the bases of which abut each other and are provided with semi-circular curved grooves 12 which when placed in registration with each other form a circular passageway for the bolts 6. The ends of these guide plates adjacent the ends of the stiffening member 1 are disposed a suitable distance therefrom and from the strap 3 to provide a space into which a tongue 13 mounted on a stop plate 14 can project. This tongue 13 is disposed above the plate 14 and is adapted to project above and parallel thereto into the space formed between the channel plates 10 and 11 and the strap 3, as shown in Fig. 3.

This tongue is provided with an aperture or bore 15 through which the bolts 6 extend. The stop plate and tongue are fastened to the bottom of the car by any suitable means, such as bolts 16. The stop plate beneath the tongue 13 and the strap 3 is provided with a recess 17 into which the end of the bolt or plunger 6 extends. It is understood, of course, that this lock construction, shown and described in Figs. 2, 3 and 4, in connection with the lower end of the stiffening member 1, is identical at the upper end of the stiffening member and that the operating arm 8, when properly moved, will lock both ends of the stiffening members simultaneously.

It will be noticed that when the door is pushed shut the reinforced ends of the post, namely, the strap 3, surrounds the tongue 13 on the stop plates 14, and by this engagement lock the door post in five directions, namely, up, down, away from the in-

terior of the car, toward the interior of the car, and in the direction of the door movement when closing. The door and post are locked in the sixth and final direction, that is of the door when opening, by means of the bolts 6. These bolts are of any suitable size and shape and are operated by any suitable means, such as that described.

This form of bolt-operated mechanism makes it practically impossible to forget to lock the door, as the mere closing of the door locks the post in five directions; and since the arm extends across the door opening when in the unlocked position, it cannot be overlooked and not moved to the locked position.

What I claim is:—

1. A door construction which includes a slidable door, a U-shaped channel member disposed on the end thereof and extending from the top to the bottom of the door, a strap disposed across the ends of the U-shaped channel member, a stop member disposed on the car adjacent each end in the channel member, a tongue on said stop member projecting into the channel member between the end thereof and the strap, said tongue and the strap having apertures aligning when the door is engaged by the stop, and means on the channel member adapted when operated to project through said apertures to lock the door to the stop member.

2. A door construction which includes a slidable door, a U-shaped channel member fastened to the end thereof and extending from top to bottom of the door, one leg of the U-shaped member being fastened against the inner face of the door, the open end of the U extending forwardly in the direction of movement of the door when closing, a strap disposed across each end of the U-shaped member and having an aperture

therein, a stop plate disposed on the car at the bottom and top of the door and having a socket therein, a tongue on said stop plate projecting parallel thereto and spaced thereabove, said tongue having an aperture therein and adapted to project into the channel member between the end thereof and the strap to align the aperture in the tongue with that in the strap and the socket in the stop plate, slidable bolts disposed at the ends of the channel members, means for guiding the movement of said bolts, and means on the channel member operated at will to project said bolts outwardly through said apertures and into said socket to lock the door from movement in a plurality of directions.

3. A door construction which includes a slidable door having an end portion, a reinforcing member fastened to said end portion and extending along its length, door stopping means fastened to the body of the car adjacent the ends of the door, and a strap on the end of the reinforcing member to engage with the stop member, the engagement of the strap and stop members locking the door in all but one possible direction of movement.

4. A door construction which includes a slidable door having an end portion, a reinforcing member fastened to said end portion and extending along its length, stop means fastened to the body portion of the car adjacent the ends of the door, a strap on the reinforcing member engaging with the stop member to lock the door in all but one possible direction of movement, and manually operated means on the end of the door to be moved into engagement with the stop member to lock the door from movement in this final direction.

HOWARD M. VAN ALSTYNE.
